ELECTRICAL SWITCH

Roscoe E. Lehman and Arden E. Roane, Hagerstown, Md., assignors to The W. H. Reisner Manufacturing Company, Hagerstown, Md., a corporation of Maryland

Application March 9, 1935, Serial No. 10,300

4 Claims. (Cl. 200—16)

Our invention relates broadly to electrical circuit controlling apparatus and more particularly to a selective circuit controlling apparatus which may be operated to control a multiplicity of co-acting circuits.

One of the objects of our invention is to provide solenoid control devices which may be compactly arranged within a relatively small area for controlling a large number of electrical circuits.

Another object of our invention is to provide a construction of solenoid switch having means shiftable to either of two limiting positions for closing an electrical circuit through contact members supported directly by the means which houses the solenoid switch.

A further object of our invention is to provide a construction of solenoid switch in which a cylindrical housing provides mounting means for axially disposed electromagnetic windings, each of which are mounted on tubular supports with their axes extending coincident with the center line of the cylindrical housing for cooperatively controlling a shiftable armature member movable to either of two limiting positions for operating a contact system.

A still further object of our invention is to provide a simplified construction of two-position electromagnetically operated switch in which a cylindrical housing carries an electromagnetic operating winding adjacent each end thereof, each adapted to coactively operate upon a movable armature member shiftable to either of two limiting positions for controlling a contact system located intermediate the electromagnetic operating windings.

A further object of our invention is to provide a construction of solenoid actuated circuit controller which may be mounted in close proximity to correspondingly constructed circuit controllers for selectively actuating a multiplicity of electrical circuits within a relatively small area.

Other and further objects of our invention reside in the electrical solenoid switches of our invention and the construction of the solenoid switches, as set forth more fully in the specification hereinafter following by reference to the accompanying drawings, in which:

Figure 1 shows a circuit arrangement in which the solenoid switches of our invention are illustrated applied to an all electric combination action for organs; Fig. 2 is an elevational view showing one method of mounting the electromagnetic switches of our invention; Fig. 3 is a

vertical sectional view taken on line 3—3 of Fig. 2; Fig. 4 is a lateral sectional view taken on line 4—4 of Fig. 2; Fig. 5 is a plan view of one of the electromagnetic switches constructed in accordance with our invention and showing the contact element in neutral position with both sets of electrical contacts open; Fig. 6 is a view corresponding to the view shown in Fig. 5 but illustrating the left hand contact system closed by movement of the armature toward the left; Fig. 7 is a side elevational view of the electromagnetic switches shown in Figs. 5 and 6; Fig. 8 is a cross-sectional view with parts shown partially in elevation taken through the electromagnetic switch on line 8—8 of Fig. 5; Fig. 9 is an end view of the electromagnetic switch shown in Figs. 5—7; Fig. 10 is a cross-sectional view taken on line 10—10 of Fig. 8; Fig. 11 is a cross-sectional view taken on line 11—11 of Fig. 8; Fig. 12 is a diagrammatic and schematic view showing the control circuit for the electromagnetic switch of our invention; Fig. 13 shows one arrangement of the contact system for the electromagnetic switch of our invention; Fig. 14 shows a modified arrangement of contact system for the electromagnetic switch of our invention; and Fig. 15 shows a further modified form of contact system which may be provided for the electromagnetic switch of our invention.

For purposes of explaining our invention, we have shown the application of our construction of electromagnetic switch to an all electric combination action for organs, but we desire that it be understood that the electromagnetic switch of our invention is applicable to various kinds of electrical control circuits.

In Fig. 1, we have shown an all electric combination action for organs in which three stop keys have been illustrated at 1, 2, and 3 arranged adjacent the control panel 4. Each stop includes a frame structure shown at 5, 6, and 7, on which there is mounted the "on" control magnets 8, 9 and 10 and the "off" control magnets 11, 12, and 13, which coact with respect to shiftable armature members 14, 15 and 16 to move contacts 14a, 15a and 16a to either of two limiting positions. We have indicated in the drawings the "off" position for the contacts and the "on" position for the contacts. The stop keys which we employ are set forth more particularly in Letters Patents No. 1,538,949, dated May 26, 1925, and No. 1,538,950, dated May 26, 1925, on the inventions of Osborne I. Price, although we desire that it be understood that other forms of stop keys may be employed.

We employ in the circuit control system, electromagnetic switches 17, 18, 19, 20, 21, and 22 of the kind set forth in Letters Patent No. 1,954,758, granted April 10, 1934, on the invention of William H. Reisner. We provide electromagnetic control switches 23, 24, 25, 26, 27, and 28 connected with the electromagnetic switches, as shown. A source of direct current is connected to terminals indicated at 29. In the organ control system, switch 17 functions as setter No. 1, and switch 18 functions as setter No. 2. Switch 19 functions as a setter to control switches 17 and 18. Switch 20 functions to control combination No. 1, and switch 21 functions to control combination No. 2. Switch 22 functions as a setter for controlling switch 20 which, in turn, controls combination No. 1, and also for controlling switch 21, which in turn, controls combination No. 2. We provide a setter control switch 30, and a switch 31 for selecting combination No. 1 and a switch 32 for selecting combination No. 2.

Electromagnetic control switches 23, 24, 25, 26, 27, and 28 include independent operating windings which will be more fully hereinafter described and which function to shift an armature member to either of two positions. The armature members for the respective switches each carry a contact pin represented in Fig. 1 at 33, 34, 35, 36, 37, and 38 which, when shifted either to the right or left, establish connection through contact systems 43, 44, 45, 46, 47 and 48, or 53, 54, 55, 56, 57, and 58 respectively.

The construction of the electromagnetic switch of our invention will be more fully understood by reference to Figs. 2-15 in which the mounting for a multiplicity of electromagnetic switches has been illustrated on panel 59. I have designated the electromagnetic switches 23, 24, 25, 26, 27 and 28, as supported in spaced parallel relation on panel 59 by means of strip members 60 and 61 which conform to the shape of the casings which enclose the electromagnetic switches and are fastened to the panel 59 by suitable screws or other means 62, as shown.

Each electromagnetic switch is enclosed by a cylindrical housing formed from insulating material which we have designated by reference character 63. The housing 63 is provided with a relatively large central opening 64 intermediate the length thereof on one side of the housing and a smaller opening or slot 65 adjacent the opposite side of the housing. The cylindrical housing 63 receives two electromagnetic systems 66 and 67. The electromagnetic system 66 is constituted by a winding wound on an insulated spool-like member 68 having an end flange 69 conforming to the internal diameter of the cylindrical housing 63 and an end flange 70 having laterally projecting lugs 71 and 72 thereon for providing terminal supports for the ends of the wires which extend from the winding 66. Each lug 71 and 72 is provided with binding members 71a and 72a which secure the ends of the winding 66 to the insulated lugs 71 and 72. The end flange 70 otherwise conforms to the internal diameter of the housing 63, provision being made for the entry of the projecting lugs 71 and 72 into a recess 73 cut in the end of the housing 63. In this way, the entire electromagnetic operating unit is maintained flush with the end of the housing. The end flanges 69 and 70 are carried on the central tubular member 74 through which the rod-like armature member 75 extends in a manner free

to shift longitudinally within the tubular member 74.

In a similar manner, we arrange the electromagnetic operating system 67 on a tubular member 76 having flanges 77 and 78 conforming to the internal diameter of the casing 63 and through which the rod-like armature 75 is free to shift. The end flange 78 carries projecting lugs 79 and 80 which enter a recess 81 in the right hand end of housing 63 and serve, by means of binding members 79a and 80a, to support the ends of the wire extending from the winding 67. Very often, these connecting ends are subject to strain and the arrangement which we provide prevents any undue strain while enabling the unit to have the connecting leads to be quickly soldered thereto.

The rod-like armature member 75 which is free to shift within tubular members 74 and 76 is limited in its movement by the abutment of contact pin 33 with the end flanges 69 and 77 or with the limits of the slot 65. As the pin 33 shifts from one limiting position to another, the pin enters between the sets of contact wire elements 43 and 53.

We have shown the contact wire elements 43 and 53 on an enlarged scale in Fig. 13 from which it will be seen that there are three independent wire members 82, 83 and 84. Each wire member is provided with a looped portion which may be secured by means of a rivet or other suitable fastening member to the housing 63. Rivet 85 extends through the loop in wire member 82 and secures the wire member in position, as shown. Rivet 86 extends through the loop in the wire member 83 and through the housing 63 for securing the wire member 83 in position, as shown. Rivet 87 extends through the loop in wire member 84 for securing wire member 84 in position, as shown. The wire members are resilient and have parallel extending jaws with extremities which spread to receive the contact pin 33 as the contact pin 33 is shifted to either of two limiting positions. With the contact pin 33 in one limiting position toward the left, the wire members 83 and 82 are shunted. With contact pin 33 shifted to the right, the shunt is removed from between wire members 82 and 83 and wire members 82 and 84 are shunted, thereby establishing an electrical circuit which may be connected to rivets 87 and 85.

A variety of contact systems may be employed such as illustrated in Figs. 14 and 15. In the arrangement shown in Fig. 14, wire element 88 having a rivet loop 89 therein, coacts with a correspondingly shaped wire element 90 having a rivet loop 90a therein. There is a corresponding contact system constituted by wire element 91 having a loop 92 therein which coacts with wire element 93 having a loop 94 therein. The wire elements 88 and 90 have portions extending parallel to each other forming resilient jaws adapted to receive contact pin 33. The wire elements 91 and 93 have resilient portions extending in parallel relation also adapted to be shunted by means of contact pin 33 when shifted to the right.

We may find it desirable to employ the contact system illustrated in Fig. 15 in which a resilient wire element 95 is secured to casing 63 by means of a rivet passing through loop 96. There are two coacting wire elements 97 and 98 having resilient portions extending parallel to the resilient wire element 95. A rivet loop 99 is provided for wire element 97 and a rivet loop 100 is provided for wire element 98 by which the wire elements 75

may be secured to the housing 63. Contact pin 33 is free to bridge the parallel gaps between wire elements 95 and 97 or between wire elements 95 and 98.

5 In Fig. 12, we have shown diagrammatically the manner in which solenoid windings 66 and 67 are selectively excited from the potential source 101 by shifting selecting switch 102 to either of the two contacts by which windings 66 and 67 are independently and selectively energized. Upon shifting switch 102 to contact 103, winding 66 is energized which moves armature 75 to the left. Upon shifting switch 102 to contact 104, winding 67 is energized which shifts armature 75 to the right. The contact pin 33 carried by armature 75 serves to control the shunting or unshunting of the contact systems for correspondingly controlling a variety of electrical circuits.

We have found the construction of electromagnetically operated switch of our invention highly practical and successful in operation and, while we have described our invention in certain of its preferred embodiments, we desire that it be understood that modifications may be made and we intend no limitations upon our invention other than are imposed by the scope of the appended claims.

What we claim as new and desire to secure by Letters Patent of the United States is as follows:

30 1. A contact system comprising a single resilient wire-like contact member fixed at substantially the middle thereof and having opposite portions thereof extending in a substantially straight line, a pair of resilient wire-like contact members disposed in longitudinal alignment and each mounted adjacent one end thereof and having a portion thereof extending parallel to and spaced from one of the opposite portions of said single contact member, and a contact pin movable to either of two limiting positions in a plane normal to the plane of said contact members for alternately bridging a selected one of said pair of wire-like contact members and said single wire-like member.

2. A contact system comprising a pair of resilient wire-like contact members of substantially U shape disposed in longitudinal alignment in spaced relation with the ends thereof adjacent, means for supporting one pair of the adjacent ends of said contact members, and a contact pin selectively shiftable to either of two limiting positions substantially in the plane of the free arms of said resilient contact members which is normal to the plane of said members. 5

3. A contact system comprising a pair of resilient wire-like contact members of substantially U shape disposed in longitudinal alignment in spaced relation with the ends thereof adjacent, means for supporting one pair of the adjacent ends of said contact members, a second pair of contact members of like form and similarly supported and disposed, with the free arms thereof spaced from but parallel to the free arms of the first pair of resilient contact members and in the same plane, and a contact pin selectively shiftable to either of two limiting positions between the free arms of said contact members in a plane normal to the plane of said U-shaped members. 10

4. A contact system comprising a pair of resilient wire-like contact members of substantially U shape disposed in longitudinal alignment in spaced relation with the ends thereof adjacent, means for supporting one pair of the adjacent ends of said contact members, a single resilient wire-like contact member supported at the middle thereof and having the opposite portions thereof extending parallel to but spaced from the free arms of said U-shaped contact members and in the plane of said U-shaped members, and a contact pin selectively shiftable to either of two limiting positions between the free arms of said U-shaped contact members and the said single contact member in a plane normal to the plane of 30 said U-shaped members. 35
